UNITED STATES PATENT OFFICE.

WILLIAM T. SULLIVAN, OF CINCINNATI, OHIO.

ARTIST'S SKETCH-BOOK.

SPECIFICATION forming part of Letters Patent No. 703,500, dated July 1, 1902.

Application filed April 7, 1902. Serial No. 101,655. (No model.)

To all whom it may concern:

Be it known that I, WILLIAM T. SULLIVAN, a citizen of the United States, residing at Cincinnati, in the county of Hamilton and State of Ohio, have invented certain new and useful Improvements in Artists' Sketch-Books, of which the following is a specification.

My invention relates to an artist's sketch-book.

10 The object of my invention is, first, to provide a book with one of the cover-leaves extended and adapted to be folded in when the book is closed. On the inner face of the folding leaf is applied water-colors, which are folded in when the book is closed and protected against soiling the adjoining book-leaf.

A second object of my invention is to adapt the book to the use of beginners or amateurs. This consists in placing figures in outline on 20 the remaining pages of the book which are used, as will be hereinafter set forth in the description of the accompanying drawings, forming a part of this specification, in which—

25 Figure 1 is a perspective view of the book in the open position with the paint-leaf extended. Fig. 2 is a perspective view of the book in a folded position.

30 A represents one of the cover-leaves; B, the opposite cover-leaf; C, the color folding leaf formed integral therewith.

35 a b c represent the book-leaves containing the outline-figures.

On the cover-leaf C is applied the different color-checks, d representing the space in 35 which the various colors are applied and are separated by marginal spaces e from the adjacent checks.

40 D represents a figure in outline to be painted, which in the present illustration is the outline of a pansy-blossom. Of course each page in the book will have a different figure in outline.

45 Beginners in painting are easily taught to shade and apply the colors, to be done in the following manner: A camel's-hair brush is moistened and rubbed over one of the color-checks. It takes up the color and is then applied to the figure in outline in the same manner as other colors are applied. These outline-figures are also useful in another way. 50 Beginners are taught to draw outlines from the copy, and thus by imitation acquire the art of drawing.

When the book is intended for amateur artists for summer sketching, as tourists, no outline-sketches are placed upon the book-leaves; but the artist has his book of colors in simplest and best form, as well as sketch-paper, all combined, it being exceedingly convenient to use and quickly folded into position 60 for transportation in a manner in which the sketches can be preserved without danger of being wrinkled or bent. Of course for amateur artists the cover-leaves are made of cardboard of sufficient strength to thoroughly protect the sketches. 65

Having described my invention, I claim—

1. An artist paint-book having a folding sheet containing a series of colors, secured to the outer marginal edge of one of its covers adapted to be folded in against the inner face of said cover-leaf, substantially as specified. 70

2. An artist paint-book having a folding sheet carrying a series of colors, each color being separated from its adjacent color by marginal spaces, said folding sheet being secured to the outer marginal edge of one of the book-covers adapted to be folded in against the inner face of said cover-leaf, substantially as specified. 75

3. An artist paint-book having a folding sheet carrying a series of colors, each color being separated from its adjacent color by marginal spaces, said folding leaf being secured to the outer marginal edge of one of the covers adapted to be folded in against the inner face of said cover-leaf, and figures in outline printed upon the book-pages, substantially as specified. 85

90 In testimony whereof I have hereunto set my hand.

WILLIAM T. SULLIVAN.
